(57) **CLAIM**

The ornamental design for a safety anchor for fall arrest line, as shown and described.

DESCRIPTION

FIG. 1 is a perspective view of a safety anchor for fall arrest line showing my new design;

FIG. 2 is a top view thereof;

FIG. 3 is a bottom view thereof;

FIG. 4 is a front elevational view thereof, the rear elevational view being a mirror image thereof; and,

FIG. 5 is a right side view thereof, the left side view being a mirror image thereof.

1 Claim, 5 Drawing Sheets

FIG. 2

FIG. 3
